(57) **CLAIM**

The ornamental design for a spectacle case, as shown and described.

DESCRIPTION

1. Spectacle case
- 1.1 : Perspective
- 1.2 : Front
- 1.3 : Back
- 1.4 : Right
- 1.5 : Left
- 1.6 : Top
- 1.7 : Bottom

1.8 : Perspective view of the spectacle holder open
 The case comprises a horizontally elongate body and a wrist strap connected at the center of the top of the body; the body has a front wall, a rear wall, and a front flap with a wavy bottom edge; the front wall of the body has a slot that defines a flexible tab for engaging with the bottom edge of the flap and holding same when the body is closed; the front wall of the body has a circular element simulating an open eye on one side of the tab, and on the other side, an almost semi-circular aperture that simulates a closed eye.
